(57) CLAIM

The ornamental design for a cosmetic brush organizer, as shown and described.

DESCRIPTION

FIG. 1 is a top, front, left perspective view of a first embodiment of a cosmetic brush organizer, showing of my new design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and

FIG. 8 is a top, front, right perspective view thereof, shown in an environment of use; and,

FIG. 9 is a top, front, right perspective view of a second embodiment of a cosmetic brush organizer.

The broken lines shown in the drawings depict portions of the cosmetic brush organizer that form no part of the claimed design. The additional broken lines shown in FIGS. 8 and 9 illustrate environment and form no part thereof.

1 Claim, 8 Drawing Sheets
